UNITED STATES PATENT OFFICE.

CLARENCE C. MARDER, OF NEW YORK, N. Y., ASSIGNOR TO AMERICAN TYPE FOUNDERS COMPANY, OF JERSEY CITY, NEW JERSEY, A CORPORATION OF NEW JERSEY.

TYPE FRACTIONS AND METHOD OF USE.

1,375,307.

Specification of Letters Patent. Patented Apr. 19, 1921.

Application filed June 27, 1916. Serial No. 106,213.

To all whom it may concern:

Be it known that I, CLARENCE C. MARDER, a citizen of the United States, residing at New York, New York county, and State of New York, have invented and discovered certain new and useful Improvements in Type Fractions and Methods of Use, of which the following is a specification.

My said invention relates to the art of printing and refers particularly to type for the formation of fractions in practising said art. It has for a purpose to overcome a number of difficulties that have been experienced by the methods and the character 10 of type heretofore employed in printing fractions, such as the difficulty in handling type of very small size, as when the fractions are made up of small separate pieces; the difficulty experienced in using type composed of a single piece for each fraction of extra width, which take up more space than desirable in good printing; the difficulty in joining sections, or separate type of the form heretofore used so as to form a perfect 15 fraction and make the result a clean and perfect print, and various other difficulties which have been experienced, as well as the necessity of carrying in stock a large supply of type, variously designed for the purpose, in order to print all fractions 20 which it may be desirable to print with a usual stock of type.

These difficulties are overcome by my said invention, which makes it possible to print 25 all possible fractions with a comparatively small number of types which are of a size and character to be easily and conveniently handled by the compositor, enabling rapid work to be done in setting up forms, all as 30 will be hereinafter more fully described and claimed.

My improved font of type for fractions comprises the comparatively few regular fractions, commonly employed, consisting of 35 $\frac{1}{1}$, $\frac{1}{2}$, $\frac{1}{3}$, $\frac{1}{4}$, $\frac{1}{5}$, $\frac{1}{6}$, $\frac{1}{7}$, $\frac{1}{8}$, $\frac{1}{9}$, $\frac{1}{10}$, $\frac{1}{11}$, $\frac{1}{12}$, $\frac{1}{13}$, $\frac{1}{14}$, $\frac{1}{15}$, $\frac{1}{16}$, $\frac{1}{17}$, $\frac{1}{18}$, $\frac{1}{19}$, $\frac{1}{20}$, $\frac{1}{21}$, $\frac{1}{22}$, $\frac{1}{23}$, $\frac{1}{24}$, $\frac{1}{25}$, $\frac{1}{26}$, $\frac{1}{27}$, $\frac{1}{28}$, $\frac{1}{29}$, $\frac{1}{30}$, $\frac{1}{31}$, $\frac{1}{32}$, $\frac{1}{33}$, $\frac{1}{34}$, $\frac{1}{35}$, $\frac{1}{36}$, $\frac{1}{37}$, $\frac{1}{38}$, $\frac{1}{39}$, $\frac{1}{40}$, $\frac{1}{41}$, $\frac{1}{42}$, $\frac{1}{43}$, $\frac{1}{44}$, $\frac{1}{45}$, $\frac{1}{46}$, $\frac{1}{47}$, $\frac{1}{48}$, $\frac{1}{49}$, $\frac{1}{50}$, $\frac{1}{51}$, $\frac{1}{52}$, $\frac{1}{53}$, $\frac{1}{54}$, $\frac{1}{55}$, $\frac{1}{56}$, $\frac{1}{57}$, $\frac{1}{58}$, $\frac{1}{59}$, $\frac{1}{60}$, $\frac{1}{61}$, $\frac{1}{62}$, $\frac{1}{63}$, $\frac{1}{64}$, $\frac{1}{65}$, $\frac{1}{66}$, $\frac{1}{67}$, $\frac{1}{68}$, $\frac{1}{69}$, $\frac{1}{70}$, $\frac{1}{71}$, $\frac{1}{72}$, $\frac{1}{73}$, $\frac{1}{74}$, $\frac{1}{75}$, $\frac{1}{76}$, $\frac{1}{77}$, $\frac{1}{78}$, $\frac{1}{79}$, $\frac{1}{80}$, $\frac{1}{81}$, $\frac{1}{82}$, $\frac{1}{83}$, $\frac{1}{84}$, $\frac{1}{85}$, $\frac{1}{86}$, $\frac{1}{87}$, $\frac{1}{88}$, $\frac{1}{89}$, $\frac{1}{90}$, $\frac{1}{91}$, $\frac{1}{92}$, $\frac{1}{93}$, $\frac{1}{94}$, $\frac{1}{95}$, $\frac{1}{96}$, $\frac{1}{97}$, $\frac{1}{98}$, $\frac{1}{99}$, $\frac{1}{100}$, $\frac{1}{101}$, $\frac{1}{102}$, $\frac{1}{103}$, $\frac{1}{104}$, $\frac{1}{105}$, $\frac{1}{106}$, $\frac{1}{107}$, $\frac{1}{108}$, $\frac{1}{109}$, $\frac{1}{110}$, $\frac{1}{111}$, $\frac{1}{112}$, $\frac{1}{113}$, $\frac{1}{114}$, $\frac{1}{115}$, $\frac{1}{116}$, $\frac{1}{117}$, $\frac{1}{118}$, $\frac{1}{119}$, $\frac{1}{120}$, $\frac{1}{121}$, $\frac{1}{122}$, $\frac{1}{123}$, $\frac{1}{124}$, $\frac{1}{125}$, $\frac{1}{126}$, $\frac{1}{127}$, $\frac{1}{128}$, $\frac{1}{129}$, $\frac{1}{130}$, $\frac{1}{131}$, $\frac{1}{132}$, $\frac{1}{133}$, $\frac{1}{134}$, $\frac{1}{135}$, $\frac{1}{136}$, $\frac{1}{137}$, $\frac{1}{138}$, $\frac{1}{139}$, $\frac{1}{140}$, $\frac{1}{141}$, $\frac{1}{142}$, $\frac{1}{143}$, $\frac{1}{144}$, $\frac{1}{145}$, $\frac{1}{146}$, $\frac{1}{147}$, $\frac{1}{148}$, $\frac{1}{149}$, $\frac{1}{150}$, $\frac{1}{151}$, $\frac{1}{152}$, $\frac{1}{153}$, $\frac{1}{154}$, $\frac{1}{155}$, $\frac{1}{156}$, $\frac{1}{817}$, $\frac{1}{818}$, $\frac{1}{819}$, $\frac$

will be readily seen that any possible fraction required with a numerator or a denominator less than 100 can readily be set up by combining the appropriate two of the en-

5 set types on vertical lines or the appropriate two of the em-set types on horizontal lines.

In both cases the types are of a size and character to be easily handled by the compositor so that fractions can be set into

10 forms rapidly and conveniently, and because of the perfect alinement of the cross lines and the connection between the cross lines on the various en-set types, a perfect result is achieved on the printed page.

15 It will be understood that the term "en-set" as used in the specification and claims means a type one-half the width of an "em-set" type and that "em-set" as used herein means a type double the width of an 20 "en-set" type, that is, two "en-set" types occupy the same width in a printed form as one "em-set" type; and the meaning of said terms is not necessarily limited to the exact mathematical dimensions as recognized in the type founding art as indicated by said terms.

It will be understood, of course, that there is rarely ever any practical need for a font of type that will set all possible fractions.

30 The most commonly used fractions, aside from the regular fractions above referred to, are the 16th, 24th, 32nd, 48th, 64th, and perhaps the 10th, 30th, 40th, 50th, 60th, etc.

As will be readily understood, a font of type 35 capable of printing all such fractions in common use would have a very large number of the above noted characters eliminated.

In other words, a font of type capable of printing all fractions required in ordinary work would have a comparatively small number of types or characters. All 40 the characters, however, have been illustrated in order to make more clear the invention or discovery of the system on which

45 a font of type may be developed for the purpose and to show how by supplying a few additional characters any font may be readily made available to print any denominational fraction required.

50 As will be noted, a leading and characteristic novelty in this invention is that the font includes a large number of unusual fractions, comprising many fractions generally termed "vulgar" fractions, that is, fractions with numerators larger than denominators.

55 In addition to these "vulgar" fractions, however, there are many that perhaps may not properly be termed "vulgar" fractions within the commonly understood meaning

60 of the term, and yet are very unusual, as, for example, $\frac{1}{1}$, $\frac{2}{2}$, $\frac{3}{3}$, $\frac{4}{4}$, etc. Also $\frac{2}{4}$, $\frac{3}{6}$, $\frac{4}{8}$, $\frac{5}{10}$, etc. Also types showing 0 for a numerator with denominators running from 1 to 0.

65 All of these characters are, however, necessary to carry out the full purpose of my

invention, as without them the various combinations required to set up even those fractions commonly employed in every-day work would not be possible.

The practical use of a font of type for 70 printing fractions such as are commonly used, the character of font that would be provided for ordinary commercial purposes, may be best illustrated as follows:

Cut-cost fractions No. 1 are so made that 75 two en-set fractions can be placed together to make fractions in the 16ths, 32ds and 64ths.

Thus: $\frac{1}{2}$ and $\frac{1}{2}$ placed together make $\frac{11}{16}$

The following commonly used characters 80 are furnished:

$\frac{1}{4}$ $\frac{1}{2}$ $\frac{3}{4}$ $\frac{1}{8}$ $\frac{3}{8}$ $\frac{5}{8}$ $\frac{7}{8}$ $\frac{1}{3}$ $\frac{2}{3}$ $\frac{1}{6}$ $\frac{5}{6}$

Special characters used for 16ths, 32ds and 85 64ths are:

Numerators: $\frac{1}{1}$ $\frac{3}{1}$ $\frac{5}{1}$ $\frac{7}{1}$ $\frac{9}{1}$

Denominators: $\frac{1}{16}$ $\frac{3}{16}$ $\frac{5}{16}$

Making $\frac{1}{16}$ $\frac{3}{16}$ $\frac{5}{16}$ $\frac{7}{16}$ $\frac{9}{16}$ $\frac{1}{32}$ $\frac{3}{32}$ $\frac{5}{32}$ $\frac{7}{32}$ $\frac{9}{32}$ 90
 $\frac{1}{64}$ $\frac{3}{64}$ $\frac{5}{64}$ $\frac{7}{64}$ $\frac{9}{64}$

The following characters on en-set are used together to make 16ths, 32ds, and 64ths when numerator is 11 or larger:

For 16ths:

Combine $\frac{1}{2}$ with $\frac{1}{6}$ $\frac{3}{6}$ $\frac{5}{6}$ for $\frac{11}{16}$ $\frac{13}{16}$ $\frac{15}{16}$

For 32ds:

Combine $\frac{1}{3}$ with $\frac{1}{2}$ $\frac{3}{2}$ $\frac{5}{2}$ $\frac{7}{2}$ $\frac{9}{2}$ to make $\frac{11}{32}$ $\frac{13}{32}$
 $\frac{1}{5}$ $\frac{1}{7}$ $\frac{1}{9}$ $\frac{1}{11}$ $\frac{1}{13}$

Combine $\frac{2}{3}$ with $\frac{1}{2}$ $\frac{3}{2}$ $\frac{5}{2}$ $\frac{7}{2}$ $\frac{9}{2}$ to make $\frac{21}{32}$ $\frac{23}{32}$ 100
 $\frac{2}{5}$ $\frac{2}{7}$ $\frac{2}{9}$ $\frac{2}{11}$ $\frac{2}{13}$

Combine $\frac{3}{3}$ with $\frac{1}{2}$ to make $\frac{31}{32}$

For 64ths:

Combine $\frac{1}{4}$ with $\frac{1}{4}$ $\frac{3}{4}$ $\frac{5}{4}$ $\frac{7}{4}$ $\frac{9}{4}$ to make $\frac{11}{64}$ $\frac{13}{64}$ 105
 $\frac{1}{5}$ $\frac{1}{7}$ $\frac{1}{9}$ $\frac{1}{11}$ $\frac{1}{13}$

Combine $\frac{2}{4}$ with $\frac{1}{4}$ $\frac{3}{4}$ $\frac{5}{4}$ $\frac{7}{4}$ $\frac{9}{4}$ to make $\frac{21}{64}$ $\frac{23}{64}$
 $\frac{2}{5}$ $\frac{2}{7}$ $\frac{2}{9}$ $\frac{2}{11}$ $\frac{2}{13}$

Combine $\frac{3}{4}$ with $\frac{1}{4}$ $\frac{3}{4}$ $\frac{5}{4}$ $\frac{7}{4}$ $\frac{9}{4}$ to make $\frac{31}{64}$ $\frac{33}{64}$ 110
 $\frac{3}{5}$ $\frac{3}{7}$ $\frac{3}{9}$ $\frac{3}{11}$ $\frac{3}{13}$

Combine $\frac{4}{4}$ $\frac{5}{4}$ and $\frac{6}{4}$ with $\frac{1}{4}$ $\frac{3}{4}$ $\frac{5}{4}$ $\frac{7}{4}$ $\frac{9}{4}$ to make the rest of the "odd" 64ths: $\frac{41}{64}$ to $\frac{49}{64}$
 $\frac{5}{64}$ to $\frac{59}{64}$ $\frac{61}{64}$ to $\frac{63}{64}$

The complete list of fractions that can be made with a font of cut-cost fractions No. 1 are $\frac{1}{1}$ $\frac{1}{3}$ $\frac{2}{3}$ $\frac{5}{6}$ and complete 8ths, 16ths, 32ds and 64ths, as follows:

$\frac{1}{4}$	$\frac{1}{32}$	$\frac{3}{32}$	$\frac{1}{4}$	$\frac{1}{16}$	$\frac{5}{16}$	$\frac{3}{16}$	$\frac{7}{16}$	$\frac{1}{8}$
$\frac{9}{4}$	$\frac{5}{32}$	$\frac{1}{4}$	$\frac{3}{16}$	$\frac{13}{16}$	$\frac{7}{16}$	$\frac{3}{16}$	$\frac{15}{16}$	$\frac{1}{4}$
$\frac{17}{4}$	$\frac{9}{32}$	$\frac{1}{4}$	$\frac{5}{16}$	$\frac{21}{16}$	$\frac{11}{16}$	$\frac{23}{16}$	$\frac{3}{16}$	$\frac{3}{8}$
$\frac{25}{4}$	$\frac{13}{32}$	$\frac{2}{4}$	$\frac{7}{16}$	$\frac{29}{16}$	$\frac{15}{16}$	$\frac{31}{16}$	$\frac{3}{16}$	$\frac{1}{2}$
$\frac{33}{4}$	$\frac{17}{32}$	$\frac{3}{4}$	$\frac{9}{16}$	$\frac{37}{16}$	$\frac{19}{16}$	$\frac{39}{16}$	$\frac{5}{16}$	$\frac{5}{8}$
$\frac{41}{4}$	$\frac{21}{32}$	$\frac{4}{4}$	$\frac{11}{16}$	$\frac{45}{16}$	$\frac{23}{16}$	$\frac{47}{16}$	$\frac{7}{16}$	$\frac{7}{8}$
$\frac{49}{4}$	$\frac{25}{32}$	$\frac{5}{4}$	$\frac{13}{16}$	$\frac{53}{16}$	$\frac{27}{16}$	$\frac{55}{16}$	$\frac{9}{16}$	$\frac{9}{8}$
$\frac{57}{4}$	$\frac{29}{32}$	$\frac{6}{4}$	$\frac{15}{16}$	$\frac{61}{16}$	$\frac{31}{16}$	$\frac{63}{16}$	$\frac{11}{16}$	$\frac{11}{8}$

Cut-cost fractions No. 2 are so made that two en-set fractions can be placed together 130

to make fractions in 12ths, 16ths, 24ths and 48ths.

Thus: $\frac{1}{4}$ and $\frac{1}{8}$ placed together make $\frac{1}{4}$

The following commonly used characters 5 are furnished:

$\frac{1}{4}$ $\frac{1}{2}$ $\frac{3}{4}$ $\frac{1}{8}$ $\frac{3}{8}$ $\frac{5}{8}$ $\frac{7}{8}$ $\frac{1}{3}$ $\frac{2}{3}$ $\frac{1}{6}$ $\frac{5}{6}$

Special characters used for 12ths, 16ths, 24ths and 48ths are:

10 Numerators: $\frac{1}{1}$ $\frac{3}{1}$ $\frac{5}{1}$ $\frac{7}{1}$ $\frac{9}{1}$

Denominators: $\frac{12}{1}$ $\frac{16}{1}$ $\frac{24}{1}$ $\frac{48}{1}$

Making $\frac{1}{12}$ $\frac{5}{12}$ $\frac{7}{12}$ $\frac{1}{16}$ $\frac{3}{16}$ $\frac{5}{16}$ $\frac{7}{16}$ $\frac{9}{16}$ $\frac{1}{24}$ $\frac{5}{24}$ $\frac{7}{24}$ $\frac{1}{48}$ $\frac{5}{48}$ $\frac{7}{48}$

15 The following characters on en-set are used together to make 12ths, 16ths, 24ths and 48ths when numerator is 11 or larger:

For 12ths:

Combine $\frac{1}{4}$ with $\frac{1}{2}$ for $\frac{11}{12}$

20 For 16ths:

Combine $\frac{1}{4}$ with $\frac{1}{6}$ $\frac{3}{6}$ $\frac{5}{6}$ to make $\frac{11}{16}$ $\frac{13}{16}$ $\frac{15}{16}$

For 24ths:

Combine $\frac{1}{2}$ with $\frac{1}{4}$ $\frac{3}{4}$ $\frac{7}{4}$ $\frac{9}{4}$ to make $\frac{11}{24}$ $\frac{13}{24}$ $\frac{17}{24}$ $\frac{19}{24}$

25 Combine $\frac{2}{3}$ with $\frac{3}{4}$ to make $\frac{23}{24}$

For 48ths:

Combine $\frac{1}{4}$ with $\frac{1}{8}$ $\frac{3}{8}$ $\frac{5}{8}$ $\frac{7}{8}$ to make $\frac{11}{48}$ $\frac{13}{48}$ $\frac{17}{48}$ $\frac{19}{48}$

30 Combine $\frac{2}{4}$ with $\frac{3}{8}$ $\frac{5}{8}$ $\frac{7}{8}$ to make $\frac{23}{48}$ $\frac{25}{48}$ $\frac{29}{48}$

Combine $\frac{3}{4}$ with $\frac{1}{8}$ $\frac{5}{8}$ $\frac{7}{8}$ to make $\frac{31}{48}$ $\frac{35}{48}$ $\frac{37}{48}$

Combine $\frac{4}{4}$ with $\frac{1}{8}$ $\frac{3}{8}$ $\frac{5}{8}$ to make $\frac{41}{48}$ $\frac{43}{48}$ $\frac{47}{48}$

The complete list of fractions that can be made with a font of cut-cost fractions No. 2 35 are complete 12ths, 16ths, 24ths and 48ths, as follows:

$\frac{1}{8}$	$\frac{1}{4}$	$\frac{1}{16}$	$\frac{1}{12}$	$\frac{5}{8}$	$\frac{1}{8}$
$\frac{7}{8}$	$\frac{1}{2}$	$\frac{3}{16}$	$\frac{5}{12}$	$\frac{11}{8}$	$\frac{1}{4}$
$\frac{13}{8}$	$\frac{7}{12}$	$\frac{5}{16}$	$\frac{1}{3}$	$\frac{17}{8}$	$\frac{3}{8}$
$\frac{19}{8}$	$\frac{5}{12}$	$\frac{7}{16}$	$\frac{11}{24}$	$\frac{23}{8}$	$\frac{1}{2}$
$\frac{25}{8}$	$\frac{13}{12}$	$\frac{9}{16}$	$\frac{7}{12}$	$\frac{29}{8}$	$\frac{5}{8}$
$\frac{31}{8}$	$\frac{2}{3}$	$\frac{11}{16}$	$\frac{17}{24}$	$\frac{35}{8}$	$\frac{3}{4}$
$\frac{37}{8}$	$\frac{19}{24}$	$\frac{13}{16}$	$\frac{5}{6}$	$\frac{41}{8}$	$\frac{7}{8}$
$\frac{43}{8}$	$\frac{11}{12}$	$\frac{15}{16}$	$\frac{23}{24}$	$\frac{47}{8}$	

As will be seen by referring to the table first above shown, the addition of 10 additional characters to any previous lot is sufficient to afford to the font facilities for

printing fractions of any other denominator than the denominators previously forming a part of said font.

Having thus fully described my said invention, what I claim as new and desire to 55 secure by Letters Patent, is:

1. A font of type for setting up fractions in printing comprising en-set type each bearing a numerator and a denominator with a line separating the numerator and the denominator formed to the edge of the type whereby when two of the types are set together a continuous line is formed, substantially as set forth.

2. Type for setting up fractions in printing comprising types each having a numerator and a denominator and types divided horizontally each formed with a complete numerator or a complete denominator, each of said last mentioned types being equal in 70 width to two of said first mentioned types, substantially as set forth.

3. A font of type for printing fractions comprising types formed on en-set bodies with successively increasing numerators and 75 successively increasing denominators and also type formed on em-set bodies each having a complete numerator or a complete denominator thereon.

4. In a font of type, fraction types comprising en-set types each having a numerator and a denominator separated by a horizontal line extending to the edges of the type and types of em-set width divided on a median horizontal line each member being 85 formed with a complete numerator or a complete denominator, the part forming the numerator having a formative line near its lower edge, whereby any desired fraction less than hundredths may be set up by the 90 employment of type-members of a size not less than an en-set.

In witness whereof, I have hereunto set my hand and seal at Jersey City, New Jersey this 20th day of June, A. D. nineteen 95 hundred and sixteen.

CLARENCE C. MARDER.

Witnesses:

F. B. BERRY,
F. K. PHILLIPS.
